STOVE DEVICE FOR AUTOMATIC CHOKE
CARBURETORSMorris C. Brown, Detroit, Mich., assignor to Carter
Carburetor Corporation, St. Louis, Mo., a cor-
poration of Delaware

Application June 23, 1938, Serial No. 215,428

7 Claims. (Cl. 123—119)

This invention relates to heat or thermostatic controls for internal combustion engines and consists particularly in novel means for mounting a heating device associated with the control.

5 A well known form of automatic choke control for internal combustion engine carburetors utilizes a thermostat mounted in a housing adjacent the carburetor air horn and a heater or stove mounted on a part of the engine, preferably the exhaust manifold, which fairly accurately reflects the temperature of the engine firing chambers, this stove being connected to the thermostat housing by a tube through which heated gases are drawn. In mounting the stove devices 10 now in use, the manifold must be drilled, or clamps must be applied. Drilling of the manifold must be accurately done and is generally undesirable. Moreover, in some cases, the manifold construction is such that application of attaching clamps is difficult, and there may be insufficient room to mount a sufficiently large heater.

An object of the present invention is to provide a stove device of the above type which may be attached to the engine exhaust manifold without the necessity of drilling a hole in the manifold or of providing clamps or other holding devices which must extend around the manifold.

Another object is to provide a novel heating device or stove of the above type which may be easily applied and may be repeatedly removed and replaced without avoiding the effectiveness of the stove or its attaching means.

Another object is to provide a high capacity stove or heating device of the above type arranged to be conveniently mounted on a portion of the engine exhaust manifold which would not be easily accessible for the purpose of drilling or applying clamps.

These objects and other more detailed objects 40 hereafter appearing are attained by the device illustrated in the accompanying drawing in which:

Fig. 1 is an inside view showing the intake and exhaust manifolds of an internal combustion engine and a portion of the carburetor, with the heater applied thereto.

Fig. 2 is a top view of the structure in Fig. 1 with the carburetor removed.

50 Fig. 3 is a vertical transverse section taken substantially on the section line 3—3 of Fig. 1.

Fig. 4 is a disassembled perspective view showing the novel heater element.

Fig. 5 is a side view showing the heater element and holding member.

Fig. 6 is a view showing the holding member alone.

The exhaust manifold 1 and intake manifold 2 are arranged for a six cylinder engine and are provided with the usual branches 3 and 4 having pads 5 and 6 for attachment to the engine block 7, adjacent the usual valve ports, an intake port being shown at 8 in Fig. 3. The two arms of the exhaust manifold merge at the center in a downwardly extending portion 9 arranged for 10 attachment to an exhaust pipe (not shown) for leading the exhaust gases to the rear of the vehicle. The three branches of the intake manifold meet at the center inside a box construction 10, forming a "hot spot" and communicating with 15 the exhaust manifold to receive hot gases therefrom.

Mounted on "hot spot" box 10 is a carburetor 11 of the automatic choke type, having a housing 12 carried adjacent the upper or air horn portion thereof and enclosing a thermostat 25 for controlling the choke valve. The interior of housing 12 is connected by means of passage 26 to the engine intake suction posterior to the carburetor throttle. An automatic choke construction of this type is disclosed in detail and claimed in Patent No. 2,085,351 issued in the name of I. E. Coffey. Hot air is conducted to thermostat housing 12 by means of an insulated tube 13 extending downwardly from the housing to an angular heater element 14 mounted on a part of the exhaust manifold immediately adjacent the engine block 7 and beneath and inside "hot spot" box 10.

The intake and exhaust manifolds are secured to the engine block by means of a series of bolts 15 and washers 16. Extending over the center branch 4 of the intake manifold is a horseshoe-shaped holding member 17 of laterally resilient material and normally bowed at the center as indicated in Fig. 5. The two center manifold attaching bolts 15 extend through elongated holes or slots 18 in the leg portions of the holding member. At the lower ends of these leg portions are provided inwardly offset lugs or fingers 19 extending into slots 20 in the stove element. The stove element also has a hole 21 for receiving the lower end of heating tube 13. The bowed construction of holding member 17 is such that when the associated manifold bolts 15 are tightened down thereupon this member is distorted from its normal shape or, in other words, is straightened, which forces the lower ends of the legs of member 17 and fingers 19 downwardly and outwardly against heater element 14 so as to 55

hold this element securely in position against the corner portion 22 of the exhaust manifold.

Stove 14, when assembled, is slightly spaced from the wall of the exhaust manifold at the center, as shown in Fig. 3, whereby an open ended chamber is formed for confining a body of air which is heated by the hot walls of the exhaust manifold. This heated air is drawn through tube 13 into the thermostat housing 12 and thence into the engine intake, as explained in the above mentioned Coffey patent.

The stove construction is firmly held in position by means of the usual manifold attaching bolts and may be removed and reassembled without avoiding the effectiveness of the stove or holding means. Obviously, the shaping of the stove element 14 may be varied to conform with the particular portion of the exhaust manifold with which it is associated and no special construction of manifolds need be provided, nor need any holes or taps be provided in the manifold to accommodate the heater. The exclusive use of all modifications as come within the scope of the appended claims is contemplated.

25 I claim:

1. In combination with an internal combustion engine having a thermostatic control, an element forming a heater chamber with a normally hot portion of the engine, means for heating said control from said chamber, and a resilient holding member secured to a part of the engine spaced from said hot portion and extending to said element for securing the same in position.

2. The combination specified in claim 1 further including a device extending transversely of said holding member and connecting the same and said engine, said member being normally bowed whereby lateral pressure thereon from said device causes application of pressure to said heater element to hold said element in position.

3. The combination specified in claim 1 further including a device extending transversely of said holding member and connecting the same and said engine, said member being of normally bowed structure whereby lateral pressure applied to said member by said device causes application of holding pressure to said heater element, said

member being resilient to permit removal from and reapplication to an engine without avoiding the effectiveness thereof for holding said heater element in place.

4. In combination with an engine including a manifold and a thermostatic control, a separately formed element forming a heater chamber with a normally hot portion of the engine, a bolt adjacent said portion securing said manifold to the engine block, means for heating said control from said chamber, and a holding member of normally bowed, laterally resilient sheet material secured to the engine by said bolt and bearing against said element to secure the same in position.

5. In combination with an engine having a branched manifold and a thermostatic control, an element forming a heater chamber with a normally hot portion of the engine, means for heating said control from said chamber, a pair of bolts spaced from said portion and securing said manifold to the engine block, and holding structure comprising a pair of normally bowed, laterally resilient members secured to the engine by said bolts and distorted by the pressure thereof so as to bear against said heater element and hold the same in position.

6. The combination as specified in claim 5 in which said holding structure is in the form of a horseshoe extending partially around one of the branches of said manifold.

7. In combination with an engine having a block, manifold structure, and a thermostatic control, a separately formed element forming a heater chamber with a portion of said structure immediately adjacent said block, said structure extending outwardly from said portion so as to render access thereto difficult, means for heating said control from said chamber, a sheet member extending along said block and engaging said heater element and a bolt securing said manifold structure and said bowed members to said engine block, said sheet member being normally bowed and being distorted by said bolt so as to apply holding pressure to said element.

MORRIS C. BROWN.
